KNITTING MACHINE CAM

John F. Thiel, Maple Shade, N. J.

Application December 15, 1937, Serial No. 179,980

2 Claims. (Cl. 66—82)

This invention relates to cams for full fashioned hosiery machines. A machine of this character employs cams on a shiftable cam shaft for the truck cam rollers to ride on under the influence of springs which prevent the speed of operation of the machine from being raised past the potential recovery power of the springs, otherwise excessive vibration coupled with poor precision will be set up bringing about a production disadvantage, the vibration also affecting quality of the work produced by the machine.

The primary object of the present invention is the provision of a multiple cam within a cam for the operation of the different motions of the machine, as for instance, the narrowing motion, the knocking over bit motion and other motions common to such a machine, so that the speed of operation of the machine may be materially increased with precision raised to the highest degree of efficiency by reducing vibration to a minimum and thereby eliminating wear and the necessity of adjustments incident thereto, and consequently prolonging the life of the machine.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a fragmentary transverse sectional view illustrating the cam constructed in accordance with the present invention shown adapted to a cam shaft of a full fashioned hosiery machine in which the cam is employed for the operation of the mechanism for the raising and lowering of needles and the working of said needles about pivots.

Figure 2 is a side elevation illustrating a cam unit.

Figure 3 is a sectional view taken on the line 3—3 of Figure 2.

Figure 4 is a side elevation illustrating one of the cams of the unit.

Figure 5 is a sectional view taken on the line 5—5 of Figure 4.

Figure 6 is a side elevation illustrating the cam unit with the cam shown in Figure 4 removed.

Figure 7 is a sectional view taken on the line 7—7 of Figure 6.

Figure 8 is a transverse sectional view show-

ing a cam unit including in the construction triple cams.

Referring in detail to the drawings, the numeral 1 indicates a fragmentary portion of a full fashioned hosiery machine wherein the needles thereof are indicated by the character 2 and the mechanism for operating the needles by the character 3. The mechanism 3 includes truck rollers 4 for actuation by a cam unit 5 forming the subject matter of the present invention. Heretofore the truck rollers have been actuated by cams on the cam shaft 6 and caused to ride said cams by spring means. In a construction of this kind the speed of operation of the machine cannot be raised past the potential recovery of the spring means, otherwise excessive vibration will be set up in the machine affecting the life of the machine as well as producing production disadvantages. A machine of the character referred to employs a number of cams for the operation of the various motions, for instance the knock over bit motion and the narrowing motion as well as the needle operation heretofore broadly referred to, all of the operating mechanisms for these motions having the truck rollers thereof riding on the cams by spring influence. To remove the above set forth disadvantages from a full fashioned hosiery machine and to permit the speed of operation to be materially increased, cam units 5 constructed in accordance with the present invention are substituted for the cams now in use wherein the spring action now is entirely eliminated and the truck rollers compelled to ride their respective cams with precision and eliminating vibration and undue wear in the machine.

The present invention is in the cam unit consisting of a multiple cam within a cam, or in other words, consists of cam elements 7 and 8 each including a hub 9 to be secured on the cam shaft 6. The cam elements are fastened together by tie bolts 10. The peripheries of the cam elements are shaped to bring about proper movement of the mechanism for operating a particular motion of the machine and portions of these peripheries are of annular formation, as shown in Figure 2, which will permit passing of the truck rollers from one cam unit to another during the shifting of the cam shaft 6 which is common in the operation of a full fashioned hosiery machine. The cam unit 7 may be termed the master unit and is extended beyond its periphery, as shown at 11, and has integral therewith a roof 12. The roof 12 overlies the peripheries of the cam elements and has faces 13 to match the

- peripheries of the cam elements so that when the truck rollers ride the cam elements they also contact the faces of the roof and are thereby caused to follow the cam elements accurately and 5 eliminate the use of springs to maintain the rollers on their cams. A cam unit constructed in this manner will permit maximum speed of operation of the machine to be obtained with vibration reduced to a minimum.
- 10 A cam unit may include two or more cam elements and, as shown in Figure 8, the cam unit includes three cam elements. The cam elements may be increased and decreased as needed in the operation of the various motions of the machine. The cam elements being detachably connected by the tie bolts 10 provide means which will permit the cam unit to be increased and decreased as to the number of cam elements desired.
- 15 20 The use of the cam unit on a modern full fashioned hosiery machine will provide in the latter the fineness of precision that is usually associated with a good watch movement. With such precision of movement and due to the multiple cams within a cam principle, control of vibration and the speed of the machine will be materially enhanced and torque may be controlled to a fraction of a degree. The necessity for adjustment and repairs will be reduced to a minimum and the delicacy of precision will enable the machine to produce work of a superb quality never before approached with a full fashioned machine operating with the conventional type of cams. Further the life of the machine will be 25 prolonged and it is to be understood that the present cam invention can be applied to any of the motions employed in a full fashioned hosiery machine.
- 30 35

What is claimed is:

1. In a full fashioned hosiery machine, a variable motion operating mechanism including a truck roller and a longitudinally shiftable cam shaft, a multiple cam unit secured on said shaft and including a master cam and a plurality of superimposed cams to be selectively engaged by the truck roller, and a roof element forming a part of the master cam but surrounding all of the cams of the unit, said roof element being separately shaped in accordance with the peripheral contour of the master cam and the respective superimposed cams whereby to retain said truck roller in its working engagement with the respective cams. 10

2. In a full fashioned hosiery machine, a variable motion operating mechanism including a truck roller and a longitudinally shiftable cam shaft, a multiple cam unit secured on said shaft and including a plurality of superimposed cams to be selectively engaged by the truck roller, the peripheral working portions of said cams being differently formed eccentrically relative to the axis of the shaft and the other peripheral portions of the cams being formed coincidentally concentric to the axis of the shaft, and an annular roof element carried by and forming a part of the unit in fixed relation to the cams thereof, said roof element overhanging and surrounding all of the cams and being separately shaped internally in accordance with the peripheral contours of the respective cams whereby to retain the truck roller in working relation to the eccentric peripheral portion of the selectively engaged cam and also in engagement with the concentric portions of the cams during the axial movement 25 of the cam shaft. 30 35
